UNITED STATES PATENT OFFICE.

MILAN KOVACHEVIĆ, OF ALLEGHENY, PENNSYLVANIA.

CABINET.

SPECIFICATION forming part of Letters Patent No. 789,327, dated May 9, 1905.

Application filed July 12, 1904. Serial No. 216,208.

To all whom it may concern:

Be it known that I, MILAN KOVACHEVIĆ, a citizen of the United States of America, residing at Allegheny, in the county of Allegheny and 5 State of Pennsylvania, have invented certain new and useful Improvements in Cabinets, of which the following is a specification, reference being had therein to the accompanying drawings.

10 This invention has relation to cabinets, and more particularly to that class which are commonly known as "memorandum-cabinets;" and this invention has for its primary object to provide a cabinet of this character which 15 will be extremely simple in construction, strong and durable, and highly efficient for the many purposes for which it may be used.

Another object of this invention is to provide a cabinet upon which memoranda may 20 be recorded, and I employ novel mechanism in said cabinet whereby a plurality of memoranda may be made and the mechanism operated to carry said memoranda within the cabinet and preserve the same.

25 A further object of my invention is to construct a cabinet of the above-described character which is particularly adapted to be used upon the exterior of buildings, novel means being employed to protect the mechanism 30 from injury. At the same time I have provided means whereby the mechanism may be removed from the cabinet should the same need attention.

Briefly described, my improved cabinet 35 consists of a rectangular casing having an inclined top, and this top is preferably hinged within the casing and is adapted to carry the mechanism which I employ for supporting and operating a roll of paper. This paper is 40 adapted to pass without the casing upon the top of the cabinet whereby a memorandum may be made upon the same, and I employ mechanism for again carrying the paper within the cabinet and preserving it until such 45 time as the same may be used. The cabinet as constructed in accordance with my invention is particularly adapted to the use of doctors and such persons as may have use for the same.

50 The above construction will be hereinafter

described in detail, and, referring to the drawings accompanying this application, like numerals of reference indicate like parts throughout the several views, in which—

Figure 1 is a side elevation of my improved 55 cabinet. Fig. 2 is a similar view with the top of said cabinet in an open position. Fig. 3 is a top plan view of my improved cabinet; and Fig. 4 is a top plan view of the cabinet when the top of the same is in an open position, as shown in Fig. 2 of the drawings.

In carrying my invention into effect I preferably form the same of a rectangular casing, this casing comprising a base 1, sides 2 and 3, and a front and rear wall 4 and 5. The 60 casing may be made of a casting which is my preferable form, or it may be made of sections comprising the walls and bottom and suitably secured together. The rear wall of the casing is made of a greater height than the other walls, 65 as designated by the reference-numeral 6, and in this wall an aperture (not shown) might be formed, whereby the casing might be hung upon a wall or suitable support. The sides 2 and 70 3 of the casing have their top edges inclined, 75 as designated by the reference-numeral 7. The side walls 2 and 3 are formed with bosses 8 upon their top edges, and in these bosses is journaled a pin 9, upon which is pivotally mounted the lid or top of the cabinet 10, said 80 lid having formed on its rear edge a boss 11, through which the pin 9 passes, and the rear edges of said lid are cut away, as indicated at 12 12, to allow the lid to be swung upon the pin 9 without interfering with the bosses 85 8 8. The side wall 3 of the casing is provided with an angular slot 14, this slot being formed to accommodate an angular bracket 15, formed integral with the lid near its forward end, 90 said bracket being adapted when the lid is in its closed position to fit within the angular slot 14. Formed integral with the top of said lid and upon each side is a U-shaped bracket 16, these brackets when the lid is in a closed position providing a support for a pencil or pen. Formed integral with the under face of the lid and upon the side opposite the bracket 15 is a vertical standard 17, to which is secured a cross-arm 18, and in the one end 95 of this cross-arm and in the bracket 15 is 100

journalized a shaft 19, upon which is mounted a roller 20. Between the roller and the bracket 15 is mounted a ratchet-wheel 21 upon the shaft 19, and the one end of the shaft 19 is adapted to protrude past the edge of the lid and has secured thereon a knob or button 22, whereby when the lid is closed upon the casing the knob may be rotated to revolve the shaft 19.

10 The reference-numeral 23 indicates a pawl, which is pivotally mounted, as indicated at 24, to the bracket 15, and this pawl is adapted to engage the teeth of the ratchet-wheel and prevent a rearward rotation of the same when the lid is closed.

Upon the under face of the lid is formed a bracket 25, which is in longitudinal alignment with the bracket 15, and in this bracket and the end 26 of the cross-arm 18 is journalized a shaft 27, upon which is mounted a roll of paper 28, the end of this paper being adapted to pass down around the boss 11 along the top surface of the lid, as designated by the reference-numeral 29, and is then adapted 25 to pass through a slot 30, formed longitudinally within the lid near its upper edge, and the end of the paper is adapted to be fastened to the roll 20, this construction being particularly shown in Figs. 3 and 4 of the drawings. Upon the top surface of the lid and at one side thereof I secure a plate 31, upon which the directions for operating the mechanism within the casing may be printed, and in order to secure the lid upon the casing, 35 whereby the mechanism cannot be tampered with, I provide a suitable lock 32 upon the upper edge of the lid and form a keyhole 33 in said lid, through which a key 34 may be inserted to lock the lid in a closed position.

40 In the accompanying drawings I have illustrated my improved cabinet as being mounted upon the top of a letter-box 35, although the same may be suspended upon a wall or mounted upon any object upon the exterior 45 of a building, or my improved cabinet may be conveniently used upon a desk.

The manner of operating my improved cabinet is as follows: Should a person desire to make a memorandum upon the sheet of paper 50 which is exposed upon the top of the cabinet, the pencil or pen may be used which is supported within the brackets 16, or the person desiring to make a memorandum may use his own pencil or pen. When a memorandum has been written upon the paper exposed, 55 the knob 22 is rotated until the shaft 19 has been sufficiently revolved to carry that portion of the paper upon which the memorandum is written beneath the lid, where it is

wound around the roller 20. This operation 6 will provide an unused portion of paper upon the lid, upon which another memorandum may be written by the same person or the next party to use the same. This operation is continued until the paper carried by the 6 roller 28 has been entirely used, at which time a new one may be mounted upon the shaft 27. Upon the owner of the cabinet returning the lid is unlocked and opened to the position shown in Figs. 2 and 4 of the drawings, at 7c which time he may remove the roller 20 to read the memorandums, or he may revolve the roller 28 to wind the paper upon said roller and read the same during its operation. Where only a few memoranda have been made 75 upon the roll during the owner's absence, this last method is preferable.

While I have herein shown my improved cabinet as being made of a preferable form, it is observed that the same may be constructed to present forms other than the one illustrated, and I wish it to be understood that the general arrangement of the rollers upon the under face of the lid and other slight changes may be made without departing from 85 the scope of the invention.

What I claim is—

1. In a memorandum-cabinet, the combination of a casing, a lid hinged at one end to said casing and spaced apart from the casing 9c at the hinged end and having a transverse open slot near the other end, a paper-roll carried by said lid, a shaft mounted on said lid, the end of the paper wound on said paper-roll passing out from the roll around the hinged 95 end of the lid and over the top of the lid and through the slot in the lid and being fastened to the said shaft.

2. In a memorandum-cabinet, the combination of a casing, a lid hinged at one end to 10c bosses on the side walls of the casing, leaving a space between the hinged end of the lid and the end wall of the casing, a paper-roll mounted on the lower side of the lid, a bracket carried on said lid, a bearing arranged opposite 105 said bracket, a shaft journalized in said bracket and said bearing, and extending beyond the side of the casing, the side of the casing being formed with a slot conforming to said bracket, the end of the paper composing said paper-roll extending around the hinged end of the lid, through a slot therein and to said shaft.

In testimony whereof I affix my signature in the presence of two witnesses.

MILAN KOVACEVIC.
